UNITED STATES PATENT OFFICE.

JOSEPH L. HERZOG, OF NEW YORK, N. Y.

DESIGN FOR A RING-TRAY.

SPECIFICATION forming part of Design No. 35,852, dated April 8, 1902.

Application filed March 11, 1902. Serial No. 97,794. Term of patent 3½ years.

To all whom it may concern:

Be it known that I, JOSEPH L. HERZOG, a citizen of the United States, and a resident of the city of New York, borough of Manhattan, in the county and State of New York, have invented and produced a new and original Design for a Ring-Tray, of which the following is a full, clear, and exact description.

Reference is to be had to the accompanying drawings, forming a part of this specification, in which—

Figure 1 is a plan view of a ring-tray, showing my design; and Fig. 2 is an edge view thereof.

The leading feature of my design for a ring-tray consists in the body having a general diamond shape, the opposite sides of which are formed in segmental curves, giving an

escalloped effect, while the opposite sides of the end portions are formed in compound curves, and in the body are slots arranged on various lines with relation to the center. In the center of the body is a panel the outline of which follows that of the body.

Having thus described my invention, I claim as new and desire to secure by Letters Patent—

The design for a ring-tray as herein shown and described.

In testimony whereof I have signed my name to this specification in the presence of two subscribing witnesses:

JOSEPH L. HERZOG.

Witnesses:

LOUIS KAUFMAN,
HARRY THOMAS.
